UNITED STATES PATENT OFFICE.

JAMES LUNDY LUPFER, OF SWATARA TOWNSHIP, DAUPHIN COUNTY, PENNSYLVANIA.

SUSPENSORY BANDAGE.

SPECIFICATION forming part of Letters Patent No. 722,121, dated March 3, 1903.

Application filed November 26, 1902. Serial No. 132,946. (No model.)

To all whom it may concern:

Be it known that I, JAMES LUNDY LUPFER, a citizen of the United States, residing in Swatara township, in the county of Dauphin 5 and State of Pennsylvania, have invented certain new and useful Improvements in Suspensory Bandages, of which the following is a specification.

My invention relates to suspensory bandages, and has for its objects to provide a bandage that is simply and inexpensively constructed, that will be worn with great comfort, and that successfully overcomes the disadvantages of the present style of bandage. 15 These objects I attain by the construction hereinafter described, and illustrated in the drawings, in which—

Figure 1 is a side view in perspective of my invention, and Fig. 2 a front view.

20 Referring to the drawings, in which similar reference characters indicate corresponding parts throughout both views, A represents the top piece, on which is secured the pouch B, made of knitted, loosely-woven, or gauze 25 fabric.

C represents the supporting-belt, made of an elastic rope, circular in cross-section, which is passed through hooks D on the ends of the top piece and an elliptical or egg-shaped link 30 E on the posterior edge of the pouch B. Said belt by passing through said hooks D and link E forms loops c and c' to surround the wearer's legs, while the ends when secured together form a loop c" to surround the wearer's 35 waist. In order to avoid the large knot that would be made by tying the ends of the belt C together, I provide a flat ribbon F at each end of the belt, which may be tied in a bow-knot, as shown, or, if desired, be provided

40 with any approved form of buckle. The object of using a belt circular in cross-section is to avoid the inconveniences arising from the use of belts of flat material, which when the skin is moist from copious perspiration 45 will stick and make movements of the body uncomfortable, not to say painful at times, as well as endangering breakage of the belt. By having the belt round this disadvantage is overcome, as well as providing for an easy 50 up-and-down adjustability of the belt, which

will roll on the skin, while a flat belt will twist and form uncomfortable ridges.

In order to tighten the edge of the pouch around the scrotum, I provide a draw-string G, which is passed around the edge of the pouch, through its meshes, and through the link E. The ends of string G are passed through loops H, secured to the top pieces A, and through holes i in the triangular plate I, secured to said top piece, after which they 60 are knotted, as shown at K. The triangular plate I is made equilateral in shape and has holes i in each of its three angles, two of which receive the ends of string G, while through the other hole are passed the stitches 65 or other means to secure the plate to the top piece A. It will be readily understood that by this arrangement the device may be tightened or loosened on the wearer without removing his clothes, as the string G not only 70 tightens the edge of the pouch B, but also exerts a tension on the belt C, which by the adjustable nature of the belt is evenly distributed throughout its length.

I prefer to make the hooks D, link E, loops 75 H, and triangular plate I of non-corrosive material—such as vulcanized rubber, celluloid, &c., or of metal covered with these materials—and to prevent the hooks D catching into the clothing of the wearer and tearing 80 them their ends may be covered by a piece of fabric L.

Having thus described my invention, what I claim is—

1. In a suspensory bandage, the combination with a pouch secured to a suitable top piece, of a draw-string through the edge of the pouch, and a triangular plate secured to said top piece having holes therein to receive the ends of said draw-string, substantially as 85 shown and described.

2. In a suspensory bandage, in combination with a top piece and a pouch secured thereto, of an elastic belt, circular in cross-section, slidably engaged to the pouch at three 90 points, a draw-string through the open edge of said pouch, and a triangular plate secured to said top piece having holes to receive the ends of said draw-string, substantially as 95 shown and described.

3. In a suspensory bandage, the combination with a pouch secured to a suitable top piece, of hooks secured to each end of the top piece, a link at the posterior portion of
5 the pouch, an elastic belt, circular in cross-section, slidably mounted in said hooks and link, a ribbon on each end of said belt adapted to be knotted or otherwise secured together, a draw-string inserted through the edge of
10 the pouch, and a triangular plate secured to said top piece having holes to receive the ends

of said draw-string, said draw-string coacting with said belt to adjust its tension when the length of the draw-string is adjusted, substantially as shown and described.

15

In testimony whereof I hereto affix my signature in the presence of two witnesses.

JAMES LUNDY LUPFER.
